UNITED STATES PATENT OFFICE.

PETER J. PAULY, JR., OF ST. LOUIS, MISSOURI.

DROP-BAR LOCK.

No. 903,880.

Specification of Letters Patent.

Patented Nov. 17, 1908.

Application filed February 10, 1908. Serial No. 415,196.

To all whom it may concern:

Be it known that I, PETER J. PAULY, JR., a citizen of the United States, residing at St. Louis, State of Missouri, have invented 5 certain new and useful Improvements in Drop-Bar Locks, of which the following is a full, clear, and exact description, reference being had to the accompanying drawings, forming a part hereof.

10 My invention has relation to improvements in drop-bar locks for jail doors (though it may with equal propriety be applied to any door), and it consists in the novel details of construction more fully set 15 forth in the specification and pointed out in the claims.

In the drawings, Figure 1 is a front elevation of a cell and jail-door showing my invention applied thereto; Fig. 2 is a horizontal section on the broken line 2—2 of 20 Fig. 1; Fig. 3 is an enlarged elevation (parts in section) showing the lug of the drop-bar against the body of the door, and showing in dotted position the same lug opposite 25 the notch of the notched bar on the free edge of the door, so as to permit the latter to swing open; and Fig. 4 is an enlarged elevational detail of the bell-crank by which the drop-bar is controlled.

30 The object of my invention is to provide a drop-bar or gravity-bar with a laterally projecting lug which for one position of the bar (preferably the lowest position) shall be disposed in the path of some portion of 35 the free end of a hinged jail-door so that it may serve as an obstruction to the oscillation of said door and thus insure against the unauthorized opening thereof; and which for another position of the bar (preferably 40 the highest position) will come in the path of a notched or recessed section of such free end, said notch or recess being of sufficient dimensions to allow the lug to pass freely therethrough and thus permit the door to be 45 swung open, the moment the door is released from the padlock which ordinarily retains the door in its locked position.

A further object of the present invention 50 is to provide simple and easily operative mechanism for controlling the bar referred to; to provide for the door a rabbet catch adjacent to the hinge axis of said door; to provide suitable means for limiting the 55 movements of the drop-bar; to protect the drop-bar against tampering and access from

without; and to provide further and other features the advantages of which will be better apparent from a detailed description of the invention which is as follows:

Referring to the drawings, C represents a 60 cell wall along which is disposed a vertically hinged door D composed of intersecting bars spaced suitable distances apart as understood in the art.

Pivoted to a bracket arm 1 at one end of 65 the series of cells (only one being shown though the invention may control several doors simultaneously) is an actuating lever 2 to the end of whose short arm is loosely and pivotally coupled the adjacent end of 70 a reciprocating controlling-bar 3 guided and supported in any suitable mechanical manner, the bar having disposed thereon a series of sockets 4 for receiving the end of one arm of a bell-crank lever 5 pivoted about a 75 stud 6 above the door D, the end of the second arm of the bell-crank being loosely received in a socket 4' of a vertically reciprocating drop-bar 7 disposed along the cell wall adjacent to the door-jamb and in proximity to the free swinging vertical edge of 80 the door when the latter is in its closed position.

The vertical movement of the drop-bar is limited by a pin 8 carried by the cell-wall 85 and operating in a vertically elongated slot 9 in the bar, the latter being protected by a channel-bar 10 secured to the cell-wall. To the drop-bar are secured a series of angle pieces 11 whose horizontal legs project laterally beyond the face of the bar, and in front, or in the path of oscillation of the door, forming locking lugs which thus prevent the door from swinging open until shifted opposite the notches r formed in the vertical 95 notched-bar 12 fixed upon the free edge of the door. When the lugs 11 register with the notches, it is apparent of course that the door will be free to swing open, the notches being of slightly larger dimension than the 100 lugs 11. The lugs 11 are free to play in the vertical slots s formed in the adjacent flange of the channel and in the plate or wall 13 to which it is secured.

The door is provided with the usual latch 105 14 and hasp 15, the hinge-joint of the door being protected by a rabbet catch-plate 16 as well understood in the art. While only one door is here shown, it is obvious that the bar 3 may be of any length, and any 110

number of drop bars may be coupled thereto depending on the number of cell-doors to be controlled.

In Fig. 1 the actuating lever is swing to 5 position to allow the drop-bar to descend to its lowest position in which event the lugs 11 will come in front of the horizontal bars of the door and thus prevent the door from swinging open; when the lever 2 is however 10 swung to the dotted position in Fig. 1, the bar 3 will be shovved rearwardly thus rocking the bell-crank in proper direction to raise the drop-bar sufficiently to bring the lugs 11 opposite the notches *r* of the several notched-bars 12, and thus permit the door to be swung 15 open.

Such structural features and details as may be shown but to which no reference is here made are understood in the art and 20 hence no description of them is required.

Having described my invention what I claim is:

1. In combination with a door hinged to swing about a fixed axis, a gravitating drop-bar disposed on the door-jamb adjacent to the free oscillating end of the door for the closed position of the door, the bar and free end of the door having coöperating lug and notch formations whereby for one elevation 30 of the bar the door is locked against movement, and for another elevation the said door is free to swing to an open position, substantially as set forth.

2. In combination with a door hinged to swing about a fixed axis, a movable bar disposed on the wall adjacent to the free oscillating end of the door for the closed position of the door, formations on the bar disposed in the path of oscillation of the door for 40 holding the door against movement for one position of the bar, the free end of the door having notches adapted to come opposite the formations aforesaid for another position of the bar whereby the door is left unobstructed 45 and free to be swung to open position and suitable mechanism for actuating the bar from a point removed from the door, substantially as set forth.

3. In combination with a jail-door hinged 50 about a fixed vertical axis, a notched bar at the free oscillating edge of the door, a vertically reciprocating drop-bar disposed adjacent said oscillating edge for the closed position of the door, a series of lugs project-

ing from the drop bar in front of the door 55 for the lowest position of the drop-bar, said lugs being adapted to come opposite the notches of the notched bar for a raised position of the drop-bar whereby the door is free to be swung to an open position, and 60 suitable mechanism for actuating the drop-bar from a point without the cell, substantially as set forth.

4. In combination with a jail-door hinged about a fixed vertical axis, a notched bar 65 upon the free oscillating edge of the door, a vertically reciprocating drop-bar mounted on the cell-wall in proximity to the vertical free edge of the door when in its closed position, a series of lugs projecting from the 70 drop-bar in front of the door for the lowest position of the drop-bar, said lugs being adapted to come opposite the notches of the notched bar for a raised position of the drop-bar, an actuating lever on the outside of the 75 cell-wall, a horizontally reciprocating controlling bar leading from one end of the lever above the cell-door, a bell-crank lever pivotally mounted above the cell-door and having its respective arms in coöperative connection 80 with the drop-bar and controlling-bar, whereby upon proper oscillation of the actuating lever the drop-bar is raised or lowered, the parts operating substantially as, and for the purpose set forth.

5. In combination with a jail-door hinged about a fixed vertical axis; a notched bar upon the free vertical edge of the door, a vertically reciprocating drop-bar mounted on the cell-wall adjacent the door-jamb and 90 having vertically disposed slots, pins operating in said slots for limiting the movements of the drop-bar, a protecting channel bar for said drop-bar, a series of locking lugs carried by the drop-bar and projecting through 95 elongated slots in the adjacent flange of the channel in front of the door, and holding the door against movement, and suitable mechanism for shifting the drop-bar to bring the locking lugs thereof opposite the notches 100 of the notched bar, whereupon the door is free to swing open, substantially as set forth.

In testimony whereof I affix my signature, in presence of two witnesses.

PETER J. PAULY, Jr.
